REFUSE TREATING APPARATUS

Francis Charles Evans, Brighton, England

Application March 16, 1933, Serial No. 661,151
In Great Britain March 16, 1932

10 Claims.

(Cl. 110—8)

My Letters Patent No. 1,729,572 covers a method of an apparatus for disposing of town refuse by dumping everything indiscriminately upon grates in a trough beneath the level of the earth, or in strata as the result of preliminary sorting and slowly burning the combustible constituents.

An object of my present invention is to provide improved apparatus for treating town refuse in the manner referred to.

10 A more specific object is to provide an apparatus in which the dumping of refuse and the heat treatment of refuse already dumped can be carried out continuously, by which I mean progressively. In other words during the time that material in one part of the trough is being heat treated, material to be treated later may be simultaneously dumped in another part or parts of the trough. A feature which contributes largely to this desirable end resides in so mounting the grates and arranging them in relation to a passageway subjacent to the trough and extending uninterruptedly along the bottom thereof that the residue upon any one grate can be discharged into the passageway without interfering with any other grate or grates in the trough and then removed from said passageway in any suitable manner. For example, the residue may be discharged from the grate or grates into a vehicle or vehicles, or on to an endless or other type of conveyor, or if of appropriate character, may be drawn off by suction.

Another feature of the invention resides in locating the grates adjacent to the lower part of a main flue running longitudinally of the trough and providing damper controlled lateral openings at intervals along such flue, above the grate level. The flue or flues of a number of troughs are conducted, say, to a chimney, natural or forced draught being employed. By means of such a flue, grates may be disposed in sets at opposite sides thereof thereby enabling a relatively wide trough to be used in conjunction with a single main flue, such trough being adapted to be charged with material from both sides.

45 Although the details of construction may be variously modified and the invention carried into effect in sundry ways, one example suitable for many services will now be described with the aid of the accompanying drawings in which:

50 Figs. 1 and 1a together represent a diagrammatic view longitudinally of the plant, Fig. 1 being mainly in elevation and Fig. 1a in section with parts removed. Figs. 2 and 2a are corresponding plan views, certain parts being removed 55 from Fig. 2a. Fig. 3 is a cross section. Fig. 4 is a view to a larger scale of a grate, being part of Fig. 3 in greater detail.

In this example ground is excavated and lined with say concrete or pise-de-terre so that throughout the length of the section shown in Figs. 1 and

2 walls 1 diverge upwardly from a central passageway 2 which is equipped with rails 3 and serves as a runway for a truck 4 or set of trucks. The excavation is, towards one end, gradually decreased in depth so that a sloping bottom 5 brings the track rails 3 to the normal ground level. A flue 6 is built and supported as by longitudinal beams 7 and cross bearers 8 above the runway in such a position that grates 9 may be hinged adjacent to each lower edge extending to the opposed diverging walls of the trough, in relation to which walls they may be normally more or less perpendicular. These grates may be held individually by any suitable means, such as a catch 10 upon a rock shaft 11 loaded by a counterweight 12, lifting of which releases the grate, the arrangement being such that any single grate can be liberated and allowed to descend and discharge the residue into a truck 4 advanced beneath it. The grates in addition to normally offering an inclined support for the material to be treated are at a height sufficient to allow the truck to travel under all. In this way it is possible to treat material at one end whilst loading at a point more remote in the length of the trough, thus proceeding until material at or near the far end is being treated, by which time the material at the commencing end of the trough will be ready for discharge or have already been discharged, when the cycle can be repeated.

20 Openings in opposite walls of the flues, fitted with vertical damper slides 13 enable the draught to be varied at different parts in the length of the trough.

The top of the main flue 6 may be above the level of the ground, hinged covers 14 proceeding from opposite sides thereof serving to close the trough, it being preferred that the number of covers should correspond to the number of grates 9 employed. The covers 14 may be provided with flanges 15 to enter channels 16, filled with sand or equivalent sealing medium, so that at their margins they shall be practically air-tight and smoke tight. Each cover is shown as fitted with an eye 17 to which is attached a flexible connection 18 provided with a counterweight 19 and passageway over a sheave 20 upon framing 21 surmounting the flue 6, such means serving to assist in lifting the covers and holding them upended while the trough is being charged.

25 The hinged grates 9 which support the portions of the charge of refuse above them and also serve as discharge doors for ashes and other solid residues as referred to may further act as draught-regulators; they are preferably each made with overlapping bars 9a attached to which are vanes 9b that can be turned to more or less close the air-way past them.

30 The example illustrated constitutes a duplex form of the plant, and a multiple plant may com-

prise several of such duplex plants arranged parallel to one another the space between any two duplex plants serving as a charging platform common to both plants.

5. Once combustion is started in a plant of the kind above described, fresh charges of refuse can be put into the trough at different points in its length and residue removed from different points of its length, without the need for stopping or starting the combustion in the trough, and thus it can be kept in continual operation, and loading and discharging of the trough can be continually proceeding if fresh charges are put in succession into successive parts of the length of the trough, and the residual products are taken from successive portions of the trough beginning with the discharge of a portion of the trough last in order of succession from that at which the last fresh charge has been inserted.

20. What I claim is:—

1. In refuse treating apparatus, an elongated refuse receiving trough having a sunken channelway extending uninterruptedly along and beneath its bottom, a horizontal flue extending along the length of said trough within the same above the level of said channelway, and a plurality of independently movable grates extending between the bottom of said flue and the walls of the trough above said sunken channelway, said flue being apertured for communication with the trough above the level of the grates.

2. In refuse treating apparatus, an elongated open-bottomed trough having a horizontal channelway therebelow and a horizontal flue above the level of said channelway each extending along its length, a plurality of independently movable grates extending across the open bottom of said trough between the bottom of said horizontal flue and a side wall of said trough; said flue, grates and trough side wall together forming the sides and bottom of a continuous elongated refuse receiving chamber communicating with the interior of said flue through lateral apertures in the latter and said channelway below the trough providing a sunken residue-receiving and air supplying passage extending uninterruptedly beneath all the movable grates.

3. In refuse treating apparatus, an elongated trough-like combustion chamber having a channel-like air delivering passageway extending uninterruptedly along its bottom, said passageway being partitioned from said combustion chamber by a plurality of separately movable grates, a flue in said combustion chamber extending horizontally therealong and apertured laterally for communication therewith, means for selectively moving individual grates to discharge solid residues of combustion from the combustion chamber into the subjacent passageway and means for removing from said passageway the residues so discharged.

4. In refuse treating apparatus, an elongated trough-like combustion chamber having a channel-like air delivering passageway extending uninterruptedly along its bottom, said passageway being partitioned from said combustion chamber by a plurality of separately movable grates, each grate comprising overlapping bars with adjustable air regulating vanes attached thereto, a flue in said combustion chamber extending horizontally therealong and apertured laterally for

communication therewith, means for selectively moving individual grates to discharge solid residues of combustion from the combustion chamber into the subjacent passageway and means for removing from said passageway the residues so discharged.

5. In refuse treating apparatus an elongated refuse receiving trough having a sunken channelway extending uninterruptedly along its bottom, a horizontal flue extending along the length and centrally of said trough above the level of said channelway and a plurality of independently movable grates extending between the bottom of said flue and the walls of the trough above said sunken channelway, said flue being apertured for communication with the trough above the level of the grates.

6. In refuse treating apparatus an elongated refuse receiving trough having a sunken channelway extending uninterruptedly along its bottom, a horizontal flue extending along the length and centrally of said trough above the level of said channelway and a plurality of independently movable grates extending between the bottom of said flue and the walls of the trough above said sunken channelway, said flue including a plurality of separately adjustable apertures communicating with the trough above the level of the grates.

7. In refuse treating apparatus an elongated refuse receiving trough having a sunken channelway extending uninterruptedly along its bottom, a horizontal flue extending along the length and centrally of said trough above the level of said channelway, movable sectional cover means extending from the top of said flue across the top of said trough and a plurality of independently movable grates located between the bottom of said flue and the walls of the trough, said flue being apertured for communication with the trough above the level of the grates.

8. In refuse-treating apparatus an elongated refuse receiving trough having a sunken channelway extending uninterruptedly along its bottom, a horizontal flue extending along the length and centrally of said trough above the level of said channelway, movable sectional cover means extending from the top of said flue across the top of said trough and a plurality of independently movable grates located between the bottom of said flue and the walls of the trough, said flue including a plurality of separately adjustable apertures communicating with the trough above the level of the grates.

9. Refuse-treating apparatus comprising a pair of inclined spaced walls constituting an elongated trough, a horizontal flue longitudinally dividing said trough into two compartments, the interior of said flue communicating with the interiors of said trough compartments through lateral apertures in said flue and the bottoms of said compartments being formed by grates interposed between said flue and said inclined walls below said lateral apertures in said flue and a channelway extending uninterruptedly along the bottom of said divided trough below said flue and said grates.

10. The refuse treating apparatus of claim 9, characterized by sectionally movable cover means for each of the two compartments of the trough.

FRANCIS CHARLES EVANS.
